His Attorney

UNITED STATES PATENT OFFICE.

LLOYD V. LEWIS, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING SYSTEM.

Application filed November 24, 1922. Serial No. 602,975.

To all whom it may concern:

Be it known that I, LLOYD V. LEWIS, a citizen of the United States, residing at Edgewood Borough, in the county of Allegheny and State of Pennsylvania, have invented certain new and useful Improvements in Railway-Traffic-Controlling Systems, of which the following is a specification.

10 My invention relates to railway traffic controlling systems, and particularly to systems of the type wherein alternating currents are supplied to the track rails and the cars or trains are provided with governing apparatus which is controlled by such current or currents in the rails. More particularly my invention relates to trackway apparatus for use in systems of this character.

15 I will describe one form and arrangement of trackway apparatus embodying my invention, and will then point out the novel features thereof in claims.

20 The accompanying drawing is a diagrammatic view showing one form of railway traffic controlling apparatus embodying my invention.

25 Referring to the drawing, the reference character 2 designates the track rails of a railway over which traffic normally moves in the direction indicated by the arrow. These rails are divided by insulated joints 1 into a plurality of track sections A—B, B—C, etc. Each track section is provided with a source of track circuit current, which, as here shown, is a secondary winding 14 of a track transformer designated by the reference character T with an exponent corresponding to the location, this secondary being connected across the rails at the exit end 30 of the section. Interposed between this secondary and one rail of the section is an impedance 13 whereby the current output of the transformer is limited to a safe value when the section is occupied by a train. 35 Each section is also provided with a track relay which is designated by the reference character R with an exponent corresponding to the location, and each of which relays is connected across the rails adjacent the entrance end of the section. It will thus be seen that each track section is provided with a track circuit comprising a transformer secondary 14, an impedance 13, the track rails 2 and the winding of a relay R.

The primary 15 of each track transformer 55 T is constantly connected with a transmission line 16 which is supplied with alternating current by a generator 17.

Each track section is also provided with a signal designated by the reference character S with an exponent corresponding to the location. Each of these signals comprises a semaphore arm which may assume three distinctive positions with respect to its mast corresponding to indications of "proceed", "caution" or "stop". Each signal is provided with a circuit controller 9 having a movable contact finger 19 controlled by the semaphore arm of the associated signal in such manner that when the semaphore arm is 60 at proceed or caution or any point intermediate these two, a contact 19—20 is closed, and when the semaphore arm is at stop a contact 19—21 is closed. Each signal is controlled by means associated therewith but 65 not essential to the complete disclosure of my invention and hence omitted from the drawing for the sake of simplicity. It is sufficient to say that when the corresponding section is occupied the signal indicates stop, 70 when the corresponding section is unoccupied but the section next in advance is occupied the signal indicates caution, and when the corresponding section and the section next in advance are both unoccupied 75 the signal indicates proceed.

80 Each track section is also provided with means for supplying the rails in parallel with another current and which I will hereinafter call "local" current. For this purpose an impedance 3 is connected across the rails adjacent the entrance end of each section. A similar impedance 5 is connected across the rails adjacent the exit end of each section and a third impedance 4 is connected 85 across the rails at an intermediate point in the section as shown in the drawings. Referring particularly to section A—B, a line transformer designated by the reference character H^b is provided with a primary 90 winding 12, supplied with current from the transmission line 16. This transformer also comprises two secondary windings 10 and 11. The winding 10 has a circuit which passes 95 from its left hand terminal a through wire 22 to the middle point of impedance 4, through both rails 2 in multiple, impedance 3, wire 23, back contact 6—8 of relay R^b,

2
and wire 24 to the right-hand terminal *b* of the secondary winding 10 of the transformer H^B . This circuit is provided with a branch which passes from wire 23 through front contact 6-7 of relay R^B , wire 26, contact 19-21 of signal circuit controller 9 and wire 25 back to wire 24. This circuit is closed when relay R^B is de-energized, or when relay R^B is energized and signal S^B is in the stop position, and in either case the rails of the section between impedances 3 and 4 will be supplied with local current of what I shall term reverse relative polarity and the portion of the section between the impedance 4 and the right-hand end of the section A-B will not be supplied with local current. The circuit for the other secondary 11 of transformer H^B passes from its left-hand terminal *a'* through wire 27, contact 19-20 of the signal circuit controller 9, wire 26, front contact 6-7 of relay R^B , wire 23, to the mid point of the impedance 3 thence through both rails 2 in multiple, impedance 5, and wire 28 back to the right-hand terminal *b'* of the secondary 11 of transformer H^B . This circuit is of course closed only when relay R^B is energized and signal S^B is either at proceed or caution, and the rails of the entire section will then be supplied with local current of opposite relative polarity and which I will therefore term current of normal relative polarity.

The trackway apparatus here shown is intended for co-operation with train carried governing apparatus which operates in the following manner: When the train is on a portion of track which is supplied with track circuit current, and with local current of normal polarity, the governing apparatus permits the train to travel at high speed, such as 60 miles per hour. When the track is supplied with track circuit current, and also with local current of reverse relative polarity, the governing apparatus prevents the train from proceeding at more than an intermediate speed, such as 35 miles per hour. But when the train enters a portion of track from which the supply of either track circuit current or local current is discontinued, the governing apparatus prevents the train from proceeding at more than a low speed such as 10 miles per hour. One form of governing apparatus which will co-operate in this manner with the trackway apparatus herein shown, is illustrated and described in United States Letters Patent No. 1,351,771 for railway traffic controlling systems, issued to Lloyd V. Lewis, September 7, 1920.

60 The operation of the entire apparatus is as follows: As shown in the drawing a vehicle X is occupying the section to the right of C. This de-energizes the track relay R^C and brings the signal S^C to the stop position whereby local current of reverse relative po-

larity is supplied to the rails of the section B-C in multiple between the impedances 3 and 4 and no local current is supplied to the rails of the section B-C between the impedances 4 and 5. The local current in the section to the right of C will depend upon traffic conditions in advance but the track circuit current is interrupted by the low resistance shunt of the wheels and axles of the train X. Due to the presence of the train X in the block to the right of C, the signal S^B is at caution, but the relay R^B is energized and local current of normal relative polarity is supplied to the rails of the section A-B. The relay R^A is energized and the signal S^A is at proceed so that the rails of the section to the left of A are supplied with local current of normal relative polarity. Thus, a train, equipped with governing apparatus of the type described above and traveling in the direction indicated by the arrow, could proceed at high speed as far as the impedance 3 in the section B-C where its speed must be reduced to the intermediate value. It could then proceed at intermediate speed till it arrived at the impedance 4 in section B-C beyond which it could not travel at speeds in excess of 10 miles per hour.

95 It will be noted that if a signal is in the stop position and its associated relay is energized, local current is supplied to the section B-C in accordance with the signal position, this being due to the branch for the circuit of transformer secondary 10. Thus 100 complete protection is afforded the train in spite of signal failures.

105 Although I have herein shown and described only one form of railway traffic controlling system embodying my invention, it is understood that various changes and modifications may be made therein within the scope of the appended claims without departing from the spirit and scope of my 110 invention.

115 Having thus described my invention, what I claim is:

1. In combination, a plurality of railway track sections, a source of track circuit current for each section, a track relay for each section, a transformer for each section having two secondary windings one of which is normally connected to the rails of the section, and means for each section controlled in part by the relay of the section next ahead for disconnecting the first secondary and connecting the second secondary with the rails of the section.

120 2. In combination, a plurality of railway track sections, a source of track circuit current for each section, a track relay for each section, a transformer for each section for supplying local current thereto and having two secondary windings one of which is normally connected to the rails of the sec- 125
130

tion, and means for each section controlled in part by the relay of the section next ahead for disconnecting the first secondary from the rails and connecting the other secondary with the rails in the reverse direction.

3. A railway traffic controlling system, comprising a plurality of successive sections of railway track, a track circuit for each section including a source of track circuit current and a relay, a transformer for each section having a secondary normally connected through impedances to points on the rails of the section adjacent the entrance and exit end thereof, a second secondary winding on each transformer, and means for each section controlled in part by the relay of the section next ahead for disconnecting the said first secondary and oppositely connecting said second secondary through impedances to the rails of the section.

4. Railway traffic controlling system, comprising a plurality of successive sections of railway track, a track circuit for each section comprising a source of track circuit current and a track relay, a signal for each section, a circuit controller operated by each signal, and means for each section controlled by said relay and said circuit controller for the section next in advance for supplying local current of normal or reverse polarity to the rails of the section.

5. A railway traffic controlling system comprising a plurality of successive sections of railway track, a transformer for each section, a secondary winding on said transformer which has one terminal normally connected to the rails adjacent the entrance end of the section and its other terminal normally connected to the rails adjacent the exit end of the section, a second secondary on said transformer; and means controlled by traffic conditions ahead for disconnecting the said first secondary and oppositely connecting the second secondary, one terminal to the rails adjacent the entrance end of the section, and the other terminal to the rails at an intermediate point in the section.

6. A railway traffic controlling system comprising a plurality of successive sections of railway track, a transformer for each section having two secondary windings, and

means associated with each section and controlled by traffic conditions ahead for connecting one or the other of the two said secondaries to the rails of the section.

7. In combination, a section of railway track, a transformer having two secondaries, and means controlled by traffic conditions in advance of said section for supplying the rails of said section with local current of one relative polarity from one of said secondaries or of the other relative polarity from the other secondary.

8. In combination, a section of railway track, a transformer having two secondaries provided respectively with terminals *a* and *a'* of like instantaneous polarity and two terminals *b* and *b'* of like instantaneous polarity, and means controlled by traffic conditions in advance of the section for connecting terminals *a'* and *b'* with the rails at the entrance and exit ends of the section respectively, or terminals *b* and *a* with the rails at the entrance end and an intermediate point in the section respectively.

9. In combination, a section of railway track; three impedances 3, 4 and 5 connected across the rails of said section at the entrance end, an intermediate point and the exit end of the section respectively; a transformer having two secondaries provided with terminals *a* and *a'* of like instantaneous polarity and two terminals *b* and *b'* of like instantaneous polarity; and means controlled by traffic conditions in advance for connecting terminals *a'* and *b'* with impedances 3 and 5 respectively, or terminals *b* and *a* with impedances 3 and 4 respectively.

10. In combination, a section of railway track; three impedances 3, 4 and 5 connected across the rails of said section at the entrance end, an intermediate point and the exit end of the section respectively; a transformer having two secondaries provided with terminals *a* and *a'* of like instantaneous polarity and two terminals *b* and *b'* of like instantaneous polarity; terminals *a* and *b'* being constantly connected with impedances 4 and 5, respectively, and means controlled by traffic conditions in advance for connecting terminals *a'* with impedance 3 or terminal *b* with impedance 3.

In testimony whereof I affix my signature.
LLOYD V. LEWIS.
